(57) **CLAIM**

We claim the ornamental design for an door with handle for merchandiser, as shown and described.

DESCRIPTION

FIG. 1 is a front left perspective view of the claimed design; FIG. 2 is a front right perspective view thereof; FIG. 3 is a front view thereof; FIG. 4 is a rear view thereof; FIG. 5 is a left side view thereof; FIG. 6 is a section view thereof taken along line 6-6 in FIG. 3; FIG. 7 is a top view thereof; and, FIG. 8 is a bottom view thereof.

The broken lines in the drawings form no part of the claimed design. Broken lines formed by equal length dashes show unclaimed subject matter. Broken lines formed of unequal length dashes (i.e., dash-dot) define bounds of the claimed design.
